UNITED STATES PATENT OFFICE.

THOMAS S. DISSTON AND HENRY DISSTON, 2D, OF PHILADELPHIA, PENNSYLVANIA, ASSIGNORS TO THEMSELVES AND HENRY DISSTON & SONS, OF SAME PLACE.

DESIGN FOR SAW-FRAME.

Specification forming part of Design No. 6,825, dated August 26, 1873; application filed August 1, 1873.

To all whom it may concern:

Be it known that we, THOMAS S. DISSTON and HENRY DISSTON, 2d, both of Philadelphia, Pennsylvania, have invented a Design for the Frame of a Pruning Saw and Knife, of which the following is a specification:

Our design for the frame of a pruning saw and knife is fully illustrated by the figure in the accompanying drawing, which represents an exterior view of the frame, the saw *x* and knife *y* being indicated by dotted lines. The rib or back *a* of the frame is curved at its outer end, as shown, and terminates in three curved projections *b*, *b*¹, and *b*², to the former of which the outer end of the saw *x* is secured, while the two latter sustain the knife *y*. The said

rib or back *a* is enlarged at its inner end to form a handle or socket, *d*, an arm, *e*, extending outward from the latter for the support of the tightening-screw *f* of the saw.

We claim—

The design for the frame of a pruning saw and knife, as represented in and by the accompanying drawing.

In testimony whereof we have signed our names to this specification in the presence of two subscribing witnesses.

THOMAS S. DISSTON.
HENRY DISSTON, 2D.
